[57] CLAIM

The ornamental design for a lace panel for a shoe, as shown and described.

DESCRIPTION

FIG. 1 is a side elevational view of a lace panel for a shoe showing my new design;

FIG. 2 is a side elevational view of the other side of the lace panel for the other side of a shoe;

FIG. 3 is a cross sectional view taken through line 3—3 of FIG. 2;

FIG. 4 is a cross sectional view taken through line 4—4 of FIG. 2; and,

FIG. 5 is a top plan view thereof.

The broken lines showing the sole and upper portion of the shoe are for illustrative purposes and form no part of the claimed design.

FIG. 1

FIG. 2

FIG. 3 FIG. 4

FIG. 5
